(57) **CLAIM**

The ornamental design for an overhead stowage bin assembly for an interior cabin of a vehicle, as shown and described.

DESCRIPTION

FIG. 1 is a perspective view of an overhead stowage bin assembly for an interior cabin of a vehicle, showing our new design; and,

FIG. 2 is a right side view of an overhead stowage bin assembly for an interior cabin of a vehicle.

The perspective view of the overhead stowage bin assembly in FIG. 1 is taken from the perspective of an observer located below and to the right of the overhead stowage bin assembly. The overhead stowage bin assembly is symmetric such that the left side view of the overhead stowage bin assembly is a mirror image of the right side view shown in FIG. 2.

The broken lines with dash-dash pattern illustrate portions of the interior cabin of the vehicle that are environmental structure and form no part of the claimed design. The broken lines with dot-dash-dot pattern represent boundaries and form no part of the claimed design.
